UNITED STATES PATENT OFFICE.

GUY ROBERTS, OF BRIDGEPORT, CONNECTICUT.

FUSE-TONGS.

1,105,043.

Specification of Letters Patent. Patented July 28, 1914.

Application filed September 20, 1913. Serial No. 790,889.

To all whom it may concern:

Be it known that I, GUY ROBERTS, a citizen of the United States, residing in the city of Bridgeport, county of Fairfield, State of Connecticut, have invented certain new and useful Improvements in Fuse-Tongs; and I do declare the following to be a full, clear, and exact description of the invention, such as will enable others skilled in the art to 10 which it appertains to make and use the same.

This invention relates to tongs, and has for its main object the production of tongs that can be readily used for handling fuses 15 and other articles without danger of crushing or otherwise damaging such articles.

The invention contemplates improvements in tongs which necessitate the employment of few parts, and in which the pivotal connection of the jaws is such that a yielding action is obtained at said connection when the article being handled is firmly grasped, thereby preventing the jaws crushing or otherwise damaging the article, yet permitting 25 said article to be held without danger of slippage or other accidental release.

In carrying out the invention as generally stated above it will, of course, be readily apparent that the essential features thereof are 30 susceptible to changes in details and structural arrangements, one simple and practical embodiment being shown in the accompanying drawings, wherein—

Figure 1 is a view in side elevation of the 35 improved tongs as they appear in use. Fig. 2 is plan view thereof. Figs. 3 and 4 are detail views of the two members of the improved tongs.

The improved tongs comprise in their general organization a two-piece structure that 40 is formed of two lengths of wire or other comparatively resilient material, one of such lengths being coiled at an intermediate point so that the convolutions of such coil form a 45 pivot journal 1, from one end of which extends the shank 2 which may form a hand-grip, or be provided with a handle 3. A jaw 4 is formed from the material that extends from the other end of the journal 1. The 50 other length of material is similarly coiled at an intermediate point, the convolutions being smaller than the convolutions of the journal 1, and form a pivot 5 that is rotatably mounted in said journal, and said pivot has 55 a shank 6, similar to shank 2, extending from

one end which may be provided with a handle 7. A jaw 8 extends from the other end of pivot 5. The jaws 4 and 8 are similar in shape, and in the examples shown are formed by bending the free portion of the material 60 in the form of a convolute curve, then bending the ends thereof transversely of the pivot and journal and returning said ends to points adjacent the convolutions of said pivot and journal. This produces jaws that 65 have concaved seats and which are especially adapted to grasp cylindrical fuses, as shown in Fig. 1 of the drawings, the fuse in such figure being designated by the numeral 9.

The action of the tongs is indicated in 70 Fig. 1, the jaws 4 and 8 embracing the fuse 9, with the handles 3 and 7 in spaced relation. In such position, the fuse is firmly held, and in the event of the handles being pressed to the position shown by dotted 75 lines in Fig. 1, the resistance offered by the fuse will be sufficient to cause the convolutions of journal 1 and pivot 5 to contract, thereby preventing crushing of the fuse.

The invention is of particular utility in 80 handling fuses and other fragile articles, and in such uses, the described manner of concaving the jaws 4 and 8 form the necessary seats in which the fuse is firmly held in position transversely of the jaws, yet through 85 the medium of the yielding pivotal connection between the two members of the tool, crushing strains can not be applied to the fuse. As a further aid to the jaws in maintaining a firm grip on the fuse, said jaws 90 may have their gripping surfaces flattened, as indicated in Fig. 3.

The handles, when used in connection with the handling of fuses and other parts of electrical work, are, of course, made of insulating material, such as wood or other non-conductors.

What I claim as my invention is:—

1. Fuse tongs composed of two members each formed from a single length of material 100 shaped to provide shanks at their inner terminals, said members having an intermediate yielding pivotal connection, the outer terminals of the members projecting forwardly from said pivotal connection and having 105 bent portions that extend transversely of the pivotal connection, the outer ends of the said bent portions being free and terminating adjacent said pivotal connection to form gripping jaws, said jaws being concaved to form 110

seats that extend transversely of the pivotal connection and the gripping surfaces of the jaws being flat.

2. Tongs composed of two members each formed from a single length of material having their inner terminals shaped to provide shanks, the members being arranged in crossing relation and having intermediate portions shaped to permit a yielding connection, the outer terminals being projected forwardly from the pivotal connection and having downwardly and upwardly bent portions, said outer terminals having portions

extending transversely of the pivotal connection and the free ends thereof having 15 downwardly and upwardly extending portions and terminating adjacent said pivotal connection to provide jaws having concaved seats that extend transversely of the tongs.

In testimony whereof I affix my signature 20 in presence of two witnesses.

GUY ROBERTS.
